PAPER CLIP

Harry Marion, Jesse A. Perlstein, and Frank J. O'Donnell, Newark, N. J.

Application November 14, 1942, Serial No. 465,603

1 Claim. (Cl. 24—261)

Our invention relates to improvements in paper clips of the resilient wire type, the principal object in view being to provide a simply constructed, inexpensive, and strong device of this character for attaching papers, and the like, together by straddling the same, and which is adapted to be applied by merely forcing the same against one edge of the papers.

To the accomplishment of the above, and subordinate objects presently appearing, a preferred embodiment of our invention has been illustrated in the accompanying drawing, set forth in detail in the succeeding description, and defined in the claim appended hereto.

In said drawing:

Figure 1 is a view in top plan of our improved paper clip in its preferred embodiment.

Figure 2 is a view in side elevation, and

Figure 3 is a view in longitudinal section taken on the line 3—3 of Figure 1.

Referring now to the drawing by numerals, our improved clip comprises a single piece of resilient wire, of any suitable gauge, bent upon itself, substantially convolutely, to provide a pair of inner and outer complemental, straight-sided loops 1, 2 of elongated form and having sides 3, 4 disposed parallel and engaging, the inner loop 2 having a rear end 5 bent at a right angle to said sides and connecting one side of the inner loop 1 with an opposite side of the outer loop 2. The loops 1, 2 are normally disposed, for the major part of their length, in a common plane.

The loops 1, 2 are formed with wedge-shaped front ends 6, 7 spaced apart longitudinally of the loops and inclining forwardly at an obtuse angle from the sides of the loops, the angle of

inclination being the same in each instance, and said ends inclining from one and the same side of the clip.

As will be clear, by merely placing the front ends 6, 7 over the edges of sheets of paper, or the like, to be clipped together and in straddling relation to such edges and forcing the clip forwardly against said edges, the loops 1, 2 will be pried apart by the edges of such sheets to clampingly engage the same.

The foregoing will, it is believed, suffice to impart a clear understanding of our invention without further explanation.

Manifestly, the invention, as described, is susceptible of modification without departing from the inventive concept, and right is herein reserved to such modifications as fall within the scope of the appended claim.

What we claim is:

- 20 A single piece clip of resilient wire including a pair of inner and outer complemental straight sided loops of elongated form having sides disposed parallel, the inner loop having a rear end disposed at a right angle to the sides thereof and connecting one side of the inner loop with an opposite side of the outer loop, said loops having wedge-shaped front edges spaced apart longitudinally of the loops and inclining forwardly and to one and the same side of the plane of the loops, said front ends inclining at an obtuse angle from the sides of the loops and at the same inclination.
